METHOD OF MANUFACTURING SANITARY DRINKING-CUPS.

1,107,348.

Specification of Letters Patent. Patented Aug. 18, 1914.

Original application filed April 4, 1912, Serial No. 658,483. Divided and this application filed October 11, 1913. Serial No. 794,708.

To all whom it may concern:

Be it known that I, JAMES POWERS, a citizen of the United States, residing at New York, in the county of New York and State 5 of New York, have invented a new and useful Method of Manufacturing Sanitary Drinking-Cups, of which the following is a specification.

This invention has reference to improvements in the method of manufacturing sanitary drinking cups, and its object is to produce a cup from thin paraffin or like paper 10 resistant to the action of water and other liquids without the aid of pastes or adhesives of any kind, and requiring but a minimum quantity of material, and which may also be so cheaply produced as to warrant discarding the cup after the use for which it is produced.

20 In accordance with the present invention a large number of cups may be produced successively from a long web of paraffin paper, simple elongated rectangular blanks being cut successively from the web, and each 25 blank is folded upon itself intermediately of its length and then the side edges where meeting are pressed together and crimped to cause cohesion of such edges, after which the joined edges are folded toward the center 30 line of the blank and pressed together and again crimped, and finally these folded edges are again folded over toward the center line of the blank and pressed together and crimped so that at the edges of the blank 35 35 the paper is folded a plurality of times upon itself under pressure, and, with crimping or like indenting action causing a strong uniting of the surfaces, it is rendered liquid-proof by the paraffin present in the paraffin 40 paper, the said paraffin being sufficiently strong to hold the parts in place. To use the cup it is compressed toward the center line to cause that end of the cup remote from the intermediate fold of the blank to spread 45 open for the reception of liquid, the folded-over side edges or margins preventing separation of the sides of the cup at such points, wherefore the cup may be used to receive liquid for immediate use or for transportation 50 for considerable distances, and, moreover, the cup may be filled several times without liability of any water or other liquid leaking therefrom.

The cup comprises but two thicknesses of

paraffin paper, while the margins where the 55 sides are folded over upon each other do not exceed five layers of paper in thickness, such thickness being to a great extent unnoticeable, although serving materially in stiffening the cup lengthwise.

60 The improved cup is readily adaptable to manufacture by very simple apparatus, so that it is readily producible in a vending machine of small size, and small cost, which may be located in public or semi-public 65 places, or wherever persons are likely to desire a cup for temporary use, and where it is common to provide a glass or cup for such use, which glass or cup is customarily used by many persons, and oftentimes without 70 any cleansing between the uses.

The invention will be best understood from a consideration of the following detailed description, taken in connection with the accompanying drawings forming a part 75 of this specification, with the further understanding that while the invention is shown as applied to a particular form of drinking cup, it is by no means limited to any strict conformity with the showing of the drawings, but may be variously changed and modified in its practical embodiments, so long as such embodiments contain no marked departure from the salient features of the invention.

85 In the drawings:—Figure 1 is a plan view of a portion of a web of paper with a severed blank adjacent thereto. Fig. 2 is a perspective view of the blank folded intermediately and disclosing the second step in 90 the process of making the cup. Fig. 3 is a perspective view illustrating the third step in the production of the cup. Fig. 4 is a perspective view illustrating the fourth and final step in the production of the cup. Fig. 95 5 is a section intermediate of the folded sides of the cup, showing the latter in the open condition. Fig. 6 is a plan view looking into the open end of the open cup. Fig. 7 is a perspective view of a means for the 100 production of the cup, such means being more or less schematically illustrated.

Referring to the drawings, there is shown in Fig. 1 a portion of a web 1 which may be considered as coming from a roll containing 105 many feet of the web, a roll being a convenient way of providing a supply of the web without danger of contamination. The web

1 is customarily a web of paraffin paper of suitable stock, although this does not preclude the use of other materials for the purpose, but as paraffin paper is one of the most convenient and cheapest materials which may be used, for the purpose, it will be considered that the cups are made of paraffin paper without, however, limitation of the invention to the use of such material. 5 From the web 1 there is severed a section 2 of suitable length to ultimately make a cup, the section 2 being substantially twice the length of the finished cup and somewhat wider than the finished cup, the latter being 10 usually produced in a flat condition to be subsequently opened up for the reception of a liquid. The web section 2, which may be considered as a blank, is usually longer than wide, and is folded intermediately of its 15 length on a line indicated by the dotted line 3 of Fig. 1, and the two ends of the blank are brought together face to face, as indicated in Fig. 2, although in the said figure the two ends of the blank are slightly separated for clearness of illustration, but, in practice, they are brought into actual contact. The marginal portions of the folded blank are now pressed together, so that the 20 paraffin coating of the paper where the pressure is applied is brought into such intimate contact as to cause more or less cohesion, and this may be enhanced by initially crimping or milling the paper when pressed together. The side portions of the folded blank are now 25 folded over on to the body of the blank, as indicated at 4 in Fig. 3, the folding being toward the longitudinal center line of the folded blank, and the folded portions 4 are subjected to pressure and are milled or 30 crimped as indicated at 5 to cause cohesion of the folded over portions of the body of the blank and the cohesion of those portions of the body of the blank overlaid by the folded over portions 5. The marginal 35 folded-over portions 5 are again folded over toward the longitudinal center line of the blank to form additional folds 6, indicated in Fig. 4, housing the folds 5, and these folds 6 are also subjected to pressure, and 40 milled or crimped to cause cohesion of the surfaces. The ordinary free edges of the sides of the folded blank of Fig. 2 are now presented toward the outer folded-over portion of the folds 6, whereby any liquid contained in the cup must, to escape, find its 45 way by a tortuous passage to such free edges, but such passage is effectually sealed by the paraffin surfaces which have been brought into close contact. The cup, therefore, comprises an elongated sheet of paper folded on itself intermediately with the side edges doubly folded on themselves to house the initially free edges of the sides, and the several surfaces where folded over are each 50 subjected to pressure, and preferably also

to a milling or crimping action whereby there is produced more or less cohesion of the paraffin, which may be present on the surface of the paper, such paraffin being sufficiently strong for the purposes of the invention, but this cohesion is brought about without the application of heat and solely by the application of pressure, while all vegetable or animal adhesives are rigidly avoided, thereby eliminating any possible substance in which disease germs might propagate should they find lodgment therein. Paraffin is, of course, wholly unsuited to the propagation of disease germs, and is not easily contaminated by any substance with which it is liable to be brought into contact in the use of the present invention, so that the cup produced is initially highly sanitary. 70 75 80

The cups as produced are substantially as shown in Fig. 4, although it will be understood that the thickness of the paper is much exaggerated, this exaggeration being necessary to illustrate the folds. It is to be observed that the folded-over sides of the cup are only as thick again as the combined thickness of the walls of the cup, and even these folded over marginal portions, together with the thickness of the cup, only make up a few thousandths of an inch. When it is desired to use the cup, pressure is applied to the outside edges of the folds 6, the pressure being directed toward the intermediate or longitudinal center line of the cup, thus bulging out the thin sides of the cup somewhat as indicated in Figs. 5 and 6, and while the cup is so held water or other liquid may be deposited therein, when the weight of the liquid will readily hold the cup in the laterally expanded condition. The cohesion of the folds where in contact effectually prevents any escape of liquid through the edges of the cup, and as the bottom fold is intact no liquid can escape therethrough, the paraffin, of course, preventing any wetting of the paper walls of the cup, since it is thoroughly resistant to any liquids which would be used within the cup. 90 95 100 105 110

The various steps of the process of making the cups are susceptible to performance by hand, or by disassociated mechanisms, but the method of manufacture is more readily carried out by a single complete machine capable of turning out a complete cup at one operation of the machine by the person desiring the cup, and such machine may be of the type known as a vending machine ordinarily locked against manipulation, but readily unlocked by the insertion of a suitable coin or the like. So far as the folding steps are concerned, they may be performed successfully by an apparatus more or less schematically shown in Fig. 7, but which is more completely illustrated and described, as well as claimed, in an application for Let- 115 120 125 130

ters Patent for an apparatus for making and vending sanitary cups filed by me on April 4, 1912, Serial No. 688,487.

In the apparatus shown in Fig. 7 the blank 2 is presented to a folding blade 7 in such manner that the blade will engage the blank intermediately and force such intermediate portion between a pair of rollers 8, these rollers having their peripheries milled, as indicated at 9, to finely crimp or otherwise impress the marginal portions of the folded blank, and at the same time feed the blank with the intermediate folded portion forward. The folded blank is presented to marginal folding devices 10 shaped to produce the fold 4, and this fold having been formed the blank is presented to other rollers 11 spaced to engage the folded portion 4 of the blank, and that portion of the body of the blank opposed to the folded portion 4, these rollers having their peripheries milled, as indicated at 12, in like manner to the milled portions 9 of the rollers 8. The rollers 11 feed the folded blank with the marginal turned-over portions 4 to other shaping members 13 constructed to produce the additional fold 6 along the sides of the blank, and after this fold is produced the blank reaches other rollers 14 having marginal milled portions 15 engaging the folds 6 and that portion of the blank opposite the folds to mill or crimp the folds 6 and the opposed portions of the body of the cup, but to suitably discharge the then completed cup into position to be accessible to the operator. The several rollers 8, 11 and 14 are so adjusted as to compress the material of the cup where engaged by the rollers to cause a coalescence or adhesion of the surfaces subjected to the pressure, whereby the paraffin of the paraffin paper is caused to coalesce to a sufficient extent to seal the folded-over portions as though united by an adhesive, the adhesion being sufficiently firm for the purposes of the present invention.

When a self contained and suitably protected mechanism is employed for the production of the cups the latter are not handled at all in any stage of the manufacture and are delivered directly to the intended user, whereby the cups are truly sanitary and individual to the user and there is no possibility of contamination of any kind as is liable to occur in the so-called sanitary cups which of necessity are practically handled by numerous persons between the time of manufacture and the time of delivery of the cup to the user.

This application is a division of application Serial No. 688,488, filed by me on April 4, 1912, for improvement in sanitary drinking cups.

What is claimed is:—

65 1. The method of producing sanitary

drinking cups which consists in first folding a blank in the form of a sheet intermediately upon itself, and then beginning at the outer edge of the intermediately folded blank folding each side toward the center line thereof a plurality of times to imprison the first fold in the second fold and thus close the sides of the cup against the escape of liquid placed therein. 70

2. The method of producing sanitary drinking cups which consists in folding a blank charged with material capable of cohesion under pressure at atmospheric temperature intermediately upon itself, and then beginning at the opposite outer side edges 80 of the folded blank folding the sides toward the center line of the blank and exerting sufficient pressure upon the side folds to cause cohesion of the material of the blank at such folds at atmospheric pressure. 85

3. The method of producing sanitary drinking cups which consists in folding an elongated rectangular blank of paper intermediate of its length, then beginning at the opposite outer edges of the folded blank 90 folding said edges toward the center line thereof and again folding the folded side edges toward the center line of the folded blank in the same direction as before to thereby imprison the first fold between the 95 second side fold and the body of the cup.

4. The method of making sanitary drinking cups from elongated blanks charged with material capable of cohesion under sufficient pressure at atmospheric temperature, which consists in first folding the blank intermediately of its length to bring the two portions of the folded blank together and compressing the marginal portions of the sides of the folded blank together, then folding over the side portions toward the center line of the folded blank and compressing said side folds, and then folding over the folded side portions of the blank toward the center line and compressing such doubly folded portions together, the pressure being sufficient to cause cohesion of the charging material of the contiguous surfaces at atmospheric temperature. 105 110 115

5. The method of making sanitary drinking cups from elongated blanks of suitable material which consists in first folding the blank intermediately of its length to bring the two portions of the folded blank together and compressing the marginal portions of the sides of the folded blank together, then folding over the side portions toward the center line of the folded blank and compressing said side folds, and then again folding over the side portions of the blank toward the center line and compressing such doubly folded portions together and against the body of the cup to be engaged thereby, the material of the cup being 120 125 130

indented each time it is subjected to pressure.

6. The method of producing sanitary drinking cups which consists in first forming a blank of paraffin paper, then folding the blank intermediately of its length, then compressing the side portions of the folded blank into intimate contact, and then folding the side portions toward the center line of the folded blank and supplying sufficient pressure to such folded portions to cause cohesion of the surfaces of the paraffin paper layers where folded at the sides of the folded blank at atmospheric temperature.

7. The method of producing sanitary drinking cups which consists in first forming a blank of paraffin paper, then folding

the blank intermediately of its length, then compressing the side portions of the folded blank into intimate contact, and then folding the side portions toward the center line of the folded blank and compressing such folded portions to cause cohesion of the paraffin paper where folded at the sides of the folded blank, the fold at each side being of double form and the paper being indented where folded.

In testimony, that I claim the foregoing as my own, I have hereto affixed my signature in the presence of two witnesses.

JAMES POWERS.
